UNITED STATES PATENT OFFICE.

PHILIP L. BECKER, OF FLUSHING, NEW YORK, ASSIGNOR TO THE AMERICAN CHICLE COMPANY, OF LONG ISLAND CITY, NEW YORK, A CORPORATION OF NEW YORK.

CHEWING-GUM PACKAGE AND METHOD OF MAKING THE SAME.

Application filed February 17, 1927. Serial No. 168,879.

My invention relates to a package and method which is more particularly adapted for use in connection with chewing-gum, candy, and other confectionery products, which are damaged by the absorption of moisture or the atmosphere.

Various packages have been proposed for the purpose, but in tests of such packages I have found that they are either impractical because of cost or because of ineffectiveness in sealing the packaged substance against the absorption of moisture or the escape of volatile oils or other ingredients of the substance.

The invention will be understood by reference to the accompanying drawings, in which

Figure 1 is a perspective view of a gum package made in accordance with the invention, and

Figure 2 is an end elevation of the same;

Figure 3 is a longitudinal section on the line 3—3, Figure 2.

In my method, I enclose the units of gum within a wrapping of paper 2, the latter being waxed, the drawing indicating the waxed coating at 3. The gum units may be individually wrapped in paper or not, as desired. The ends of the wax-paper wrapping should be folded in any approved manner, as, for example, in the manner illustrated at 4, Figure 3. Although in the drawing I have indicated the waxed coating of the paper (at 3) as applied to one of the surfaces of the paper only, it is, in practice, customary to apply the coating to both sides of the paper, and the invention contemplates the use of such paper in addition to the paper coated on one face only.

The usual "waxed paper" is a paper which has been coated with paraffin, and my invention contemplates the use of paper thus coated or paper coated with other material having the same purpose.

I have found that waxed paper when folded about the sticks of gum in the customary manner, with the overlapping portions of the paper sealed together, or merely brought into close association, and whether the sealing is effected with paraffin or other wax, or by glue, will not produce the results sought. The reason for this is that the commercial waxed papers, even when manufactured with the greatest care, have minute openings which are sufficient to either admit

moisture or permit the escape of the volatile ingredients of the substances packaged. A further difficulty is that the folding of the paper about the substance to be packaged disturbs the wax coating and provides additional minute openings. Such a condition has long been recognized in the art, and means for meeting the problem was proposed in a patent to W. A. Beatty, No. 1,369,159 of February 22, 1921, which consists in associating the paraffin paper in an envelope or wrapper of metal foil having its overlapping edges and folds sealed by paraffin or other wax. Such a package, however, is expensive because of the use of metal foil, and a further disadvantage is the weight of the package, which also is due to the use of foil. A still further objection to the use of foil lies in the fact that in the use of packaging machines, which are commercially essential in packaging chewing-gum, there is a marked tendency for the foil to become torn or punctured by the machine, thus making a break in the protecting medium, with the result that a large percentage of the packages is not moisture or air proof. The foil also has the same tendency as waxed paper, i. e., to fracture at points in the lines of fold.

By the present invention, I dispense with the foil and yet provide a package which is entirely moisture-proof and proof against the passage of air or volatile ingredients contained in the substances packaged. This is accomplished by providing a skin or coating which completely envelops the package, and which I have indicated at 5, Figure 3. I have discovered that it is not practicable to produce the package by dipping the same in molten paraffin or the like, because the paraffin or other bath has the peculiar effect of causing the initial paraffin coat on the paper to expand, swell, and otherwise tend to free itself from the paper, as by dissolving, melting, or other action. The result is that, while superficially the coating appears to be regular, it is actually irregular and not of the character required to insure the result. This is particularly true in the case of the wrapping of low-priced packages of chewing-gum and candy, where, for commercial purposes, the wrapping, dipping, and cooling operations must be performed by high-speed machinery.

In order to overcome this problem, I employ as the initial wax coating for the paper a paraffin or wax of relatively high melting

point, for example 138 degrees to 145 degrees F., or I add to the wax of ordinary melting point a percentage, for example ten per cent, of a wax of higher melting point such as carnauba wax, added to paraffin, which wax of higher melting point has, I have discovered, the function of holding the softer wax against undue flow relatively to the paper when the package is dipped in the bath for forming the coating 5. And I employ for the coating 5 a paraffin or other wax-like material which has a melting point substantially below the melting point of the initial waxed coating on the paper, for example a melting point of from 123 degrees to 130 degrees F.

My invention has the substantial advantage over the packages which have been proposed or are now in use in that the package 20 is entirely moisture and air proof, and proof against the passage of highly volatile oils such as those contained in the flavoring of the substances packaged; it avoids the use of foil, which is expensive, and it is light in 25 weight as compared with a foil package.

It will be understood that the package shown in the drawing is illustrative only, and that various modifications may be made in the form of the package within the spirit of the invention; what I claim and desire to secure by Letters Patent being as follows:—

1. A moisture and air tight package comprising a body enclosed within a wrapper of waxed paper, the paper being folded about said body, and a wax-like material completely enveloping said paper and having a melting point relatively less than that of the wax on the paper underlying it.

2. The method of producing a moisture and air proof package comprising the step of enclosing the body to be packaged within a covering of waxed paper and the further step of forming upon said paper an integral sheath of material having a melting point lower than the melting point of the wax on the paper, and cooling the package thus formed.

In testimony whereof, I have signed my name to this specification.

PHILIP L. BECKER.
